UNITED STATES PATENT OFFICE.

NAPOLEON DU BRUL, OF CINCINNATI, OHIO.

CIGAR-PACKER'S PRESS.

SPECIFICATION forming part of Letters Patent No. 574,404, dated January 5, 1897.

Application filed July 31, 1896. Serial No. 601,133. (No model.)

To all whom it may concern.

Be it known that I, NAPOLEON DU BRUL, a citizen of the United States, and a resident of Cincinnati, in the county of Hamilton and State of Ohio, have invented certain new and useful Improvements in Cigar-Packers' Presses and Bundling-Frames Therefor, of which the following is a specification.

My invention relates to improvements on the cigar-packer's press forming the subject-matter of Letters Patent No. 224,208, issued February 3, 1890, to Frederick C. Miller, of Newport, Kentucky, in which a frame or casting is employed which is formed with a base which supports a standard provided with a housing projecting over the base and having mounted therein a vertically-tubular non-rotating sliding nut, connected with a lever-operating mechanism, and in which works a screw-stem carrying a top presser-head or platen for pressing a bundle of cigars.

My invention also relates to improvements on the cigar-packer's press and bundling-frame therefor forming the subject-matter of Letters Patent No. 529,254, issued November 13, 1894, to Edgar J. Fink, of Hanover, Pennsylvania, in which is employed side presser-heads as well as a top presser-head, all connected with the lever mechanism which operates the top presser-head.

The object of my invention is to simplify the construction of the side pressing devices and bundling-frame and the means whereby the side pressing devices are connected with the lever-operating mechanism.

My improvement consists in novel features of construction hereinafter described and claimed whereby the said object is attained.

In order that my invention may be fully understood, I will proceed to describe it with reference to the accompanying drawings, in which—

Figure I is a perspective view of my improved cigar-packer's press and bundling-frame therefor. Fig. II is a perspective view of the bell-crank lever by which the upper rock-shaft is connected with the operating link or bar which is connected with the lower rock-shaft. Fig. III is a front view of the machine, showing parts in section. Fig. IV is a top view thereof. Fig. V is a vertical transverse section of the same on the line V

V, Fig. III. Fig. VI is a vertical transverse section on the line VI VI, Fig. III. Fig. VII is a detail top view of the lower rock-shaft, 55 showing the right and left cam-slot blocks. Fig. VIII is a perspective view of my bundling-frame seated on the base. Fig. IX is a top view thereof, partly broken away, the base being omitted. Fig. X is a vertical 60 longitudinal section of the same seated on the base and shown in connection with the side presser-heads on the line X X, Fig. IX.

The main frame of the press is a hollow casting or column formed with a base 1, with 65 a standard 2 surmounting the base and with a boxing 3 located at the top of the standard and overhanging the base, the frame simulating in shape an inverted T as viewed from the front of the machine. The base 1 is formed 70 with bearings 4 for a lower rock-shaft 5, which extends lengthwise of the base, and with surrounding hollow bearing-boxes 4^a at the ends of the base.

6 are hollow segmental blocks formed with 75 right and left cam-slots 6^a, respectively, mounted on the lower rock-shaft and secured rigidly thereto by cross-pins 7, so as to oscillate with the rock-shaft within the bearing-boxes. Mounted on the middle portion of the rock- 80 shaft 5 and secured by means of a pin 8 is a crank-arm 9, projecting toward the rear of the base. Journaled at one side of the boxing 3 is an upper rock-shaft 10, having a crank-arm 11 located on the inner side of the box- 85 ing, and a lever-arm 12, providing an operating-handle located on the outer side of the boxing.

13 is a pendent bell-crank lever supported by its heel 13^a on the crank-pin 11^a of the 90 bell-crank-arm 11. The short arm 13^b of the bell-crank lever is coupled by a pivot-pin 14 with the upper end of a pendent link or bar 15, which is connected by means of a crank-pin 16 with the crank-arm on the lower rock-shaft. 95 Thus when the upper rock-shaft is oscillated a similar movement will be imparted to the lower rock-shaft. Extending vertically through the boxing 3 is a tubular non-rotating sliding nut 17, having check-plates 17^a at 100 its lower end carrying a pivot-pin 18, connecting the lower end of the sliding nut with the lower end of the long arm 13^c of the bell-crank lever. Thus when the lever-arm is operated

the sliding nut is reciprocated. Mounted in the sliding nut 17 is an adjustable screw-stem 19, carrying at its lower end a top presser-head or platen 20, secured thereto by a staple 20^a or any other suitable means. The upper end of the screw-stem is provided with an operating-handle 21.

22 is a set-screw located on the opposite side of the sliding nut to the check-plates 17^a and 10 working through a threaded boss 17^b for binding the screw-stem to the sliding nut when the former is adjusted in the latter for regulating the distance between the top presser-head and the base of the press in which the 15 presser-head is permitted to travel. The bearing-boxes 4^a each support a horizontal tubular non-rotating sliding nut 23, which is formed with an upper internally-screw-threaded boss 23^a and with a lower internally-20 screw-threaded square boss 23^b. The square bosses guide the nuts in their movements in the bearing-boxes 4^a. The bearing-boxes are each formed with a longitudinal slot 4^b, in which the lower boss of the sliding nut moves 25 back and forth, while the cap-plates 4^c of the bearing-boxes are each formed with a longitudinal slot 4^d, in which the upper boss of the sliding nut moves back and forth.

Mounted in each horizontal nut is an adjustable screw-stem 24, carrying at its inner 30 end a side presser-head 25, secured thereto by a staple 25^a or any other suitable means, and at its outer end an operating-handle 26. The horizontal nuts are reciprocated by means of 35 the segment-blocks, the nuts being connected therewith by the means now described.

27 is a pendent arbor formed with a screw-threaded inner end 27^a, by which it is secured to the lower boss, with an angular collar 27^b, 40 by which it is inserted in the boss, and with a spindle 27^c, providing an axle on which is mounted an antifriction-roller 28, supported by a washer 29 and a cross pin or key 30 and working in its cam-slot when the lower rock-shaft is oscillated.

31 are set-screws having face-blocks 31^a and 45 adjustable in the upper bosses and binding on their respective screw-stems 24 when the latter have been adjusted to the proper distance from the sides of the bundling-frame.

My bundling-frame is applied and constructed as follows:

40 is a longitudinally-divided bottom plate formed on its under side with a transverse 55 channel 40^a, by which it is fitted over a transverse rib 4^b, formed on the base, and on its upper side with parallel dovetail grooves 40^b, one groove being located in each section.

41 is a handle for manipulating the outer 60 section of the plate in separating the frame. Mounted on this bottom plate are vertical sectional side blocks 42, formed with dovetail tongues 42^a, by which they are fitted to the dovetail grooves of the bottom plate and are 65 adapted to slide freely back and forth thereon. Secured to these side blocks 42 by screw-bolts 43 are inner horizontal sectional blocks

44, having interlocking fingers 44^a. The front horizontal blocks 44 are secured in any desired position by thumb-screws 45, working 70 in the front wall of the bottom plate and binding on the dovetail tongues 44^b thereof. Surmounting the horizontal blocks are two plates 46, preferably of steel and adapted to ride one over the other and cover the joint between the meeting ends of the fingers. 75

47 are sectional side plates having guide-cleats 48 secured thereto and adapted to slide between the side and horizontal blocks with their cleats fitting in channels formed in the 80 side blocks and providing guides for the sliding plates. To adapt the bundling-frame to press an octagon bundle of cigars, I provide removable lower corner-blocks 49 and upper corner-blocks 50. The lower corner-blocks are connected with the horizontal blocks by means of dowel-pins 51, passing through the cover-plates, and the upper corner-blocks are connected to the upper ends of the sliding plates by dovetail joints 50^a. 85 Screw-bolts 52 extend across the space between the side blocks and horizontal blocks for securing them together, and are surrounded by distance-sleeves 53, which are straddled by the side plates and the cleats on the side 90 plates, which have vertical recesses 48^a for this purpose. The side presser-heads are recessed at 25^b and 25^c, respectively, for the vertical blocks and vertical cleats. 95

It will be understood that all the screw-stems work in sliding nuts in a similar manner to the sliding nut and screw-stem shown in the Miller patent referred to. Instead of the operating-lever acting directly upon the horizontal nuts, the latter are provided with 100 rollers which run in cam-slots of segmental blocks which are connected to a rock-shaft underneath the machine. The lever arm or handle fastened to the upper rock-shaft when pulled down brings down the vertical 105 nut with the top presser-head, and at the same time it brings down the connecting link or bar and rotates the lower rock-shaft on which the segmental blocks are fastened and operates the two horizontal nuts simultaneously toward each other to cause the side 110 pressure-heads to operate, as will be readily understood.

The bundling-frame receives the cigars 115 when in extended position, and after the cigars have been placed therein is put into the press, where the three screw-stems are supposed to have been already adjusted to the pressure required to be given to the cigars, and the lever-arm brought down, which 125 presses the bundling-frame on each side as well as on the top simultaneously.

It will be seen that the side plates of the bundling-frame are upheld by friction and are pressed down into the space left between 130 the side and horizontal blocks and are guided by the distance-sleeves, which are straddled by the bifurcated cleats. The four corners of the bundling-frame being made removable,

square bundles, as well as octagon bundles, can be pressed in the bundling-frame. The bundling-frame is made in large and small sections, so that the small section can remain 5 on the back part of the press in an extended condition, while the cigars are placed in the larger sections. After a larger section has received the proper number of cigars the front section is pushed against the rear section 10 and the press is brought into action. While under the proper pressure the front thumb-screws are turned to tighten the front section to its pressed position. Then the lever-arm is raised, which relieves the pressure 15 from the rear section, as well as the front section, of the bundling-frame; but the front section having been kept to its pressed condition by means of the thumb-screws retains the cigars in their pressed condition. The 20 front section is then pulled away from the rear section and leaves the ends of the bundled cigars projecting to allow a band of paper which may have been stuck together to form a ring of the proper size to be slipped 25 on the end of the bundle of cigars. A ribbon may also be used on the exposed end of the bundle of cigars, to be tied as may be desired, so as to retain the cigars in their pressed condition. Of course it will be understood that 30 the cigars are left under pressure for a certain length of time until they are set. By mounting the side plates so as to slide vertically I avoid the necessity of employing extensible sections in connection therewith, as 35 required by the construction shown in the Fink patent referred to.

Having thus fully described my invention, the following is what I claim as new therein and desire to secure by Letters Patent:

40 1. A cigar-packer's press comprising a tubular non-rotating vertically-sliding nut having a stem provided with a top presser-head, the tubular non-rotating horizontally-sliding nuts each having a stem provided with a side 45 presser-head, the base having surmounting stationary bearing-boxes on which the horizontally-sliding nuts reciprocate, and mechanism whereby all the nuts are slid bodily simultaneously; substantially as described.

50 2. A cigar-packer's press comprising a tubular non-rotating vertically-sliding nut having a screw-threaded stem provided with a top presser-head, and means for adjusting the stem, the tubular non-rotating horizontally-sliding nuts, each having a screw-threaded stem provided with a side presser-head and means for adjusting the stem, the base having 55 surmounting stationary bearing-boxes on which the horizontally-sliding nuts reciprocate, and mechanism whereby all the nuts are slid bodily simultaneously; substantially as described.

60 3. A cigar-packer's press comprising vertically and horizontally sliding nuts provided 65 with presser-heads, the horizontal rock-shaft having a crank-arm, the cam-blocks mounted on the rock-shaft and connected with the hori-

zontally-sliding nuts and mechanism connected with the crank-arm and with the vertically-sliding nut whereby all the nuts are 70 operated simultaneously, substantially as described.

4. A cigar-packer's press comprising a vertically-sliding nut provided with a top presser-head, an upper rock-shaft having a crank-arm and a lever-arm, a bell-crank lever connecting the crank-arm of the upper rock-shaft to the vertically-sliding nut, the lower rock-shaft having a crank-arm, the pendent link connecting the bell-crank lever to the 80 crank-arm of the lower rock-shaft, the blocks mounted on the lower shaft having right and left cam-slots, the horizontally-sliding nuts provided with side presser-heads, and pendent arbors secured to the horizontally-sliding 85 nuts and working in the cam-slots of the blocks; substantially as described.

5. A cigar - packer's press comprising a frame having a base formed with surmounting stationary bearing-boxes a standard, and 90 an upper bearing-box located at the top of the standard and overhanging the base, the tubular vertically-sliding nut having a stem provided with a top presser-head and located in the upper bearing - box and the tubular 95 horizontally-sliding nuts each having a stem provided with a side presser-head, and located on the lower bearing-boxes, and means whereby all the nuts are reciprocated simultaneously; substantially as described. 100

6. A cigar - packer's press comprising a frame having a base formed with bearing-boxes and a standard formed with an upper bearing-box, the vertically-sliding nut provided with a top presser-head and extending 105 through the upper bearing the bell-crank lever connected to the vertically-sliding nut, the upper rock-shaft connected to the bell-crank lever, the pendent link connected to the bell-crank lever, the lower rock-shaft connected to the link, the blocks having cam-slots and mounted on the lower rock-shaft, and the horizontally-sliding nuts provided with side presser-heads, mounted on the lower bearing-boxes, and having arbors working in 110 115 the cam-slots of the blocks; substantially as described.

7. A cigar - packer's press comprising a frame having a base formed with end bearing-boxes, the lower rock-shaft having a crank-arm and mounted in the base, the hollow cam-blocks having right and left cam - slots respectively, the horizontal sliding nuts provided with side presser-heads and mounted on the bearing-boxes, the pendent arbors 120 secured to the horizontal sliding nuts and provided with antifriction - rollers working in the cam-slots, the upper rock-shaft having a crank-arm and lever-arm, the vertically-sliding nut provided with the top presser-head, the bell-crank lever connected to the vertically-sliding nut, and to the crank-arm of the upper rock-shaft and the pendent link connecting the bell-crank lever to the crank- 125 130

arm of the lower rock-shaft; substantially as described.

8. A bundling-frame comprising a bottom plate, the sliding side blocks having tongue-and-groove-joint connection with the bottom plate, the sliding horizontal blocks having interlocking fingers, and tongue-and-groove-joint connection with the bottom plate and secured to the side blocks, the side plates sliding between the blocks, and the thumb-nuts whereby the horizontal blocks are secured immovably to the bottom plate; substantially as described.

9. A bundling-frame comprising a bottom plate, the sliding side blocks having tongue-and-groove-joint connection with the bottom plate, the sliding horizontal blocks having interlocking fingers and tongue-and-groove-joint connection with the bottom plate and secured to the side blocks, the side plates sliding between the blocks, the plates mounting the horizontal blocks and covering the joints between the latter; substantially as described.

25 10. The bundling-frame comprising a bottom plate, the sliding side blocks having vertical channels and tongue-and-groove-joint connection with the bottom plates, the sliding horizontal blocks having interlocking fingers and tongue-and-groove-joint connection with the bottom plate, and secured to

the side blocks, and the side plates sliding between the blocks and having cleats fitting in the vertical channels of the side blocks; substantially as described.

35 11. A cigar-packer's press comprising the bundling-frame comprising a bottom plate, the sliding side blocks having vertical channels, the sliding horizontal blocks having interlocking fingers and secured to the side blocks, the side plates sliding between the blocks and having cleats fitting in the vertical channels, and the side presser-heads having recesses fitting the side blocks and cleats; substantially as described.

45 12. A bundling-frame comprising side blocks, horizontal blocks having interlocking fingers, side plates sliding between the blocks, and the corner-blocks secured respectively to the horizontal blocks and to the side plates; substantially as described.

50 13. A divided bundling-frame comprising a sectional bottom plate, sliding rear sections having sliding side plates, sliding and removable front sections, having sliding side plates and the sectional covering-plate; substantially as described.
